UNITED STATES PATENT OFFICE

HARRY E. NORVIEL, OF ANDERSON, INDIANA, ASSIGNOR TO DELCO-REMY CORPORATION, OF ANDERSON, INDIANA, A CORPORATION OF DELAWARE

SWITCH

Application filed December 9, 1929. Serial No. 412,739.

This invention relates to switches designed to control a plurality of circuits.

One of the objects of the instant invention is to provide a switch structure of the rotary or oscillatable type adapted to be operated by a push-pull movement of the controller.

A further object of this invention is to provide a push-pull actuator adapted to move a contact actuator assembly into a plurality of positions.

Further objects and advantages of the present invention will be apparent from the following description, reference being had to the accompanying drawings wherein a preferred embodiment of one form of the present invention is clearly shown.

In the drawings:

Fig. 1 is a rear elevation of a switch device involving the instant invention, and is substantially that view illustrated by the arrow 1 of Fig. 2.

Fig. 2 is a longitudinal section through the switch device substantially as indicated by the line and arrows 2-2 of Fig. 1.

Fig. 3 is a sectional view through the switch device substantially as indicated by the line and arrows 3-3 of Fig. 2, the contact plate being shown in the off position.

Fig. 4 is a similar view along the same line, but showing the contact plate moved into one of the circuit completing positions.

Fig. 5 is a view similar to Fig. 4, with the contact plate moved to a second circuit completing position.

Fig. 6 is an elevational view of the switch structure substantially as indicated by the arrow 6 of Fig. 2.

Fig. 7 is a section through the switch device showing the actuator assembly in elevation substantially as indicated by the line and arrows 7-7 of Fig. 2.

Fig. 8 is a detail of the driving cup contributing to the instant invention.

With particular reference to the drawing, 20 indicates an attaching bracket which may be formed of sheet metal to provide a shelf portion 21 and apertured attaching ears 22 which provide means for attaching the structure to a dash or instrument panel 23 as by the bolt and nut device 24. To the shelf por-

tion 21 of the bracket is secured a cup shaped housing 25 that has a back wall 26 in conjunctive relation with the shelf 21 and apertured at 27 for the reception and actuation of a driving cup 60 presently to be described. 55 A switch back 28 providing a plurality of terminal lugs 29 exterior of the back 28, and fixed contact points 30 within the case, operates to close the housing 25 and may be secured thereon by tangs 31 circumferentially spaced about the housing and received in grooves or notches 32 of the switch back. The switch back when assembled with the housing 25 forms a substantially parallel wall with the bottom 26, and is apertured at 33 coaxial with the aperture 27 for reception and guidance of the driving cup heretofore referred to.

Within the housing provided by the cup 25 and the switch back 28, there is a contact actuating assembly mounted for rotatable or oscillatable engagement with the fixed contacts 30 of the switch back, and that has driving engagement with the cup heretofore mentioned. This assembly comprises the 70 contact plate 35 here illustrated as of triangular form, at the several apexes of which are formed the semi-spherical contact points or buttons 36 adjacent attaching tangs 37 that have seating and clinching engagement 75 with notches 38 circumferentially disposed about the periphery of a dielectric supporting plate 39, as illustrated in Figs. 2 and 7. Both the contact plate and the dielectric member are centrally apertured as at 40 and 41 respectively for passage of the heretofore mentioned driving cup.

At points intermediate the notches 38 of the plate 39, the same is provided with additional notches 42 which loosely receive the 90 driving tongues 43 of a driving plate 44, that is also apertured at 45 for disposition about the said driving cup. In addition to the tongues 43 the plate 44 is provided with extensions or lugs 46 that are concentric with 95 the central aperture 45 and operate to centrally dispose a spring 47 interposed between the said plate 44 and the dielectric member 39 prior to assembling the same. The contact supporting member 39 and the driving 100

plate 44 are secured in their relative position, yet axially movable relative to one another by turning the ends of the driving tongues 43 inwardly of the dielectric plate substantially as indicated at 48 in Fig. 2. Thus, it will be seen that when the contact actuator assembly is confined within the housing between the cup 26 and the switch back 28, that the contact plate 35 with the points 36 will be maintained in engagement with the surface of the switch back 28, while the driving plate 44 will be maintained in engagement with the bottom 26 of the housing 25. This provides for slight axial movement of the contact supporting assembly relative to the switch back and case bottom as the contact plate moves over any inequalities of surface on the switch back.

In addition to the above appointments the driving plate 44 is provided with a tongue 50 projecting into the central aperture 45, and the bottom of the case 26 is provided with a similar tongue 51 projecting inwardly from the edge of the aperture 27. These tongue members provide for mating and driving engagement between the housing and the driving plate through the cooperation of a driving cup 60, the details of which are illustrated in Fig. 8. The driving cup 60 is of substantial dimension to be freely movable through the aligned apertures of the switch back 28 and the casing bottom 26, and the side walls thereof are provided with slots 61 and 62 which have interfitting engagement 35 with the tongues 50 and 51 respectively, just described. The driving cup is mounted in the structure so as to be freely movable in a lineal direction through the apertures 27 and 33 of the housing and back respectively, and 40 so that the tongue 50 will be disposed within the slot 61 while the tongue 51 will be disposed in the slot 62.

To the head or bottom 63 of the cup, a coupling member 64 is secured as by a rivet 45 65, and provides the attaching ears 66 to which a push-pull controller may be attached and led through the instrument panel 23 substantially as indicated in dashed lines of Fig. 2. The coupling member 64 provides the 50 oppositely disposed ears 67 which operate as stops against the shelf 21 of the attaching bracket. It will be noted from the illustration of Figs. 2 and 8, that the slots 61 and 62 are of different character, that is, the 55 groove 61 is one of spiral formation, while the slot 62 is straight. These slots in cooperation with the respective tongues 50 and 51 provide a differential splined engagement between the cup bottom and the contact actuator assembly. One of the slots and tongue provisions operates to restrain the driving cup 60 from rotation relative to the bracket and housing 25 in its movement therethrough, while the other slot and tongue engagement 60 65 operates to cause a change in the angular

position of the contact support assembly relative to the switch back upon movement of the driving cup through the parts 26 and 28 of the enclosure.

It is obvious from the drawings that movement of the controller, and thus the driving cup as illustrated in Fig. 2 will produce a rotation or oscillation of the contact plate 35 from the off position as illustrated in Fig. 3 to the first circuit closing position illustrated in Fig. 4 and thence to the second circuit closing position illustrated in Fig. 5, whenever the controller is moved from the inward position illustrated in Fig. 2 to that of the fully withdrawn position. In Figs. 3, 4 and 5 the relative position of the tongues 50 and 51 are shown in dotted lines for the purpose of illustrating the relative movement of the parts that takes place when the switch device is actuated. Of course during movement of the controller from the extended position to that of fully depressed, or the reverse of the movement that has just been outlined, the contact plate 35 will be returned to the off position as illustrated in Fig. 3.

While the form of embodiment of the present invention as herein disclosed, constitutes a preferred form, it is to be understood that other forms might be adopted, all coming within the scope of the claims which follow.

What is claimed is as follows.

1. In an electric switch the combination comprising, a casing, a bracket supporting said casing in spaced relation to a supporting panel, a switch back closing said casing, and a driving cup fixed for axial movement through said bracket, housing and switch back, said driving cup supporting a coupling member to which an actuating rod may have driving engagement from the reverse side of said panel.

2. In an electric switch, the combination comprising, a casing and switch back providing a housing having substantially parallel walls, said walls being coaxially apertured and supporting a driving cup for axial movement therethrough, a driving cup, contact closing means supported for rotation relative to said cup, said driving cup having differential spline engagement with said case and contact closing means.

3. In an electric switch, the combination comprising, a casing and switch back providing a housing having substantially parallel walls, said walls being coaxially apertured and supporting a driving cup for axial movement therethrough, a driving cup, contact closing means supported for rotation relative to said cup, said driving cup having differential spline engagement with said case and contact closing means, the differential spline engagement causing the contact closing means to rotate upon lineal motion of said cup.

4. In an electric switch, the combination comprising, a housing and switch back providing a pair of parallel walls, a driving cup fixed for lineal movement through said parallel walls and supporting circuit closing means within the housing, said driving cup having differential spline engagement with said housing and circuit closing means, whereby a change in angular position of the 10 circuit closing means relative to said switch back is produced, upon lineal movement of said driving cup.
5. In an electric switch, the combination comprising, a housing and a switch back enclosing contact completing means, a driving cup fixed for movement through apertures in opposite walls of said enclosures, said driving cup providing slots engaged by tongues on said housing and contact completing 15 means, whereby the contact completing means is caused to move angularly upon rectilinear movement of said cup.
6. In an electric switch, the combination comprising, a casing, a driving cup movable 20 through said casing, means in said casing supporting a plurality of contacts, contact closing means within said casing movable about said driving cup, and means coupling said driving cup with said contact closing means, whereby rotation of the latter is produced upon reciprocation of said cup.
7. In an electric switch, the combination comprising, a switch case provided with a switch back, said case and back being centrally apertured, and a driving cup with a coupling mounted for movement in said apertures, contact closing means within the case movable about said driving cup, said driving cup and case having cooperating provision 30 whereby the cup is restrained from rotation relative to said housing, and means whereby said contact closing means is caused to rotate relative to said cup upon movement of said cup through the apertures of said housing.
- 40 8. In an electric switch, the combination comprising, a casing, and means providing a switch back for said casing, a driving cup mounted for movement through an aperture of said casing, and contact closing means 45 within the casing driven by said cup, said casing providing a tongue extending in a slot of said cup to prevent rotation of said cup relative to said housing.
- 50 9. In an electric switch, the combination comprising, a housing, a driving cup mounted for movement through said housing, and a driving plate mounted for actuation by said cup, a movable contact supported by said driving plate and being axially movable 55 thereof, a switch back for said housing providing terminals engageable with said contact plate, and means carried by said driving plate urging said contact plate into engagement with said terminals, said driving plate
- providing locating and centering means for said urging means.
10. In an electric switch, the combination comprising, a housing and switch back enclosing contact actuating means, said contact actuating means comprising a driving plate and a dielectric member, with interposed means urging said contact plate into engagement with said switch back, a plurality of lugs stuck up from said drive plate for locating said urging means.
11. In an electric switch, the combination comprising, a housing and switch back enclosing a contact actuator assembly, said actuator assembly including a drive plate and a dielectric contact supporting plate, means disposed between said driving plate and contact supporting plate for urging the plate into engagement with said switch back, said driving plate having provisions coaxial thereof for positioning said urging means.
12. In an electric switch, the combination comprising, a dielectric member supporting a contact plate, said contact plate formed to provide a plurality of contact points and having extensions at said points for securing said contact plate to the dielectric member.
13. In an electric switch, the combination comprising, a housing and switch back enclosing a contact actuator assembly, said actuator assembly including a drive plate and a dielectric contact supporting plate, a contact plate, said contact plate formed to provide a plurality of contact points and having extensions at said points for securing said contact plate to the dielectric member.
14. In an electric switch, the combination comprising, a casing, a bracket supporting said casing in spaced relation to a supporting panel, a switch back closing said casing, and a driving cup fixed for axial movement through said bracket, housing and switch back, said driving cup supporting a coupling member to which an actuating rod may have driving engagement from the reverse side of said panel, and means manifest upon movement of said cup for actuating a contact closing member into and out of engagement with portions of said switch back.
15. In an electric switch, the combination comprising, a housing and a switch back enclosing contact completing means, a driving cup fixed for movement through apertures in opposite walls of said enclosure, said cup having oppositely disposed slots in cooperative engagement with tongues of said housing and circuit completing means, whereby said circuit completing means is actuated upon movement of said driving cup.
16. In an electric switch, the combination comprising, a housing and a switch back enclosing contact completing means, a driving cup fixed for movement through apertures in opposite walls of said enclosures, said cup having slots in cooperative engagement with

tongues of said housing and circuit completing means, whereby said circuit completing means is rotated upon movement of said drive cup.

5. 17. In an electric switch, the combination comprising, a housing and a switch back enclosing contact completing means, a driving cup fixed for movement through apertures in opposite walls of said enclosures, said cup
10 having slots in cooperable engagement with tongues of said housing and circuit completing means, said slots providing differential spline engagement between the casing and circuit completing means, whereby said circuit completing means is rotated relative to said casing upon lineal movement of said cup.

15 18. In an electric switch, the combination comprising, a housing and a switch back enclosing contact completing means, a driving cup fixed for movement through apertures in opposite walls of said enclosure, said cup having slots in cooperable engagement with tongues of said housing and circuit completing means, one of said cup slots being straight
20 and another slot being spiral, whereby differential spline connection is made between the casing and the circuit completing means.

25 19. In an electric switch, means for optionally completing circuits therethrough, comprising in combination, a casing, a driving cup, and a circuit completing assembly, said cup having differential spline connection with said case and circuit completing means, whereby said circuit completing means
30 is movable into selective positions by predetermined movement of said cup.

In testimony whereof I hereto affix my signature.

HARRY E. NORVIEL.
